UNITED STATES PATENT OFFICE.

JAMES R. GRUBB, OF WILLIAMSTON, SOUTH CAROLINA.

WASTE-PROOF-TRAVELER MAGAZINE.

932,983.

Specification of Letters Patent. Patented Aug. 31, 1909.

Application filed May 6, 1909. Serial No. 494,217.

To all whom it may concern:

Be it known that I, JAMES R. GRUBB, a citizen of the United States, residing at Williamston, in the county of Anderson and State of South Carolina, have invented certain new and useful Improvements in Waste-Proof-Traveller Magazines, of which the following is a specification.

It is well known that in cotton mills there is a considerable waste of travelers due to their tendency to link or become bunched. The travelers are ordinarily kept in open cups secured to the spinning frames and when the operatives require a traveler it becomes necessary to withdraw a bunch from the cup and disentangle one of the travelers therefrom. A number of the surplus travelers of the bunch drop upon the floor during the disentangling operation, and careless operatives often fail to return the remainder to the cup. Furthermore, these bunches of travelers are sometimes thrown by the operatives at each other out of mischief.

The present invention aims to preclude this waste and to this end provides an improved magazine which is designed to contain a supply of travelers in bulk and embodies novel means for disentangling bunches and delivering the travelers one by one, as required for use. The magazine is also arranged to be locked in order to prevent the operatives from having access thereto, but this locking mechanism does not prevent the magazine from being expeditiously refilled when the supply of travelers has become exhausted.

With these and other objects in view that will more fully appear as the description proceeds, the invention consists in certain constructions and arrangements of the parts that I shall hereinafter fully describe and then point out the novel features of in the appended claims.

For a full understanding of the invention and the merits thereof and also to acquire a knowledge of the details of construction, reference is to be had to the following description and accompanying drawing, in which:

Figure 1 is a perspective view of my improved traveler magazine; Fig. 2 is a top plan view thereof with the cover removed and the spindle in section; Fig. 3 is a vertical longitudinal section; Fig. 4 is a top plan view showing the disk arranged in superposed relation to the bottom plate; and, Fig.

5 is a fragmentary sectional view illustrating the use of a relatively thick carrier disk.

Corresponding and like parts are referred to in the following description and indicated 60 in all the views of the drawing by the same reference characters.

My improved device consists essentially of a magazine or hopper which embodies a vertically disposed cylinder 1 that is provided at its lower end with an outstanding flange 2 to which a bottom plate 3 is removably secured by means of screws or other suitable fastening elements 4. The bottom plate has an extension 5 that projects rearwardly beyond the magazine and is apertured, as shown, to admit of the device being readily attached to a convenient portion of the spinning frame.

Located within the magazine is a core-piece 6 which is disposed radially inwardly from the vertical wall of the cylinder and terminates at its upper and lower ends flush with the same, the parts being preferably cast or otherwise formed of integral structure. A segmental space is thus provided within the magazine for containing the travelers in bulk. The opposing walls of the magazine and the core-piece are formed with vertical channels or recesses 7, the said channels being correspondingly arranged, whereby the space for containing the travelers is alternately relatively wide and narrow, as best seen in Fig. 2, for a purpose to be hereinafter disclosed.

A carrier disk 8 is mounted to rotate over the bottom plate 3 and is accommodated in a recess 9 formed in the lower end of the cylinder, the recess being substantially of the same depth as the thickness of the disk, 95 in order to admit of the marginal portions of the latter underlapping the vertical walls of the cylinder and to further permit the disk to pass freely beneath the core-piece 6. The disk is formed with an annular series 100 of perforations 10 which are arranged concentrically with the segmental space in the magazine and are each designed for the reception of a single traveler, the disk being adapted to be turned, so as to cause the perforations to successively assume positions beneath the core-piece 6 and in registry with an outlet provided in the bottom plate 3 at this point. In the present instance, the outlet comprises an inclined way 11 which 110 leads into a shallow cup 12 which projects horizontally forwardly from the magazine

and is formed integral with the bottom plate at a point diametrically opposite to the extension 5.

The carrier disk 8 is operated through the instrumentality of a spindle 13 which is journaled in a vertical bore 14 formed in the core-piece and substantially coincident with the axis of the cylinder, the spindle also extending through the registering central openings 15 and 16 of the disk and bottom plate respectively. The spindle is reduced at its lower extremity, as indicated at 17, so as to provide a downwardly facing shoulder which bears against the disk 8 around the central opening 15, the said opening being of smaller diameter than the bore 14 and the opening 16. A knob 18 screws on the threaded extremity of the spindle and is of such a size as to pass through the opening 16 in the base plate, by virtue of which arrangement the knob may be tightened to clamp the disk between the same and the shoulder provided by said reduced portion. The knob is locked on the spindle against any loosening movement by means of a screw 19. A second knob 20 is formed integral with the upper end of the spindle, thus admitting of the latter being turned from above or below the magazine, according as found most convenient.

In order to prevent access to the magazine and to insure against the admission of lint or other foreign particles, I employ a cover plate 21 which is loosely mounted upon the spindle between the knob 20 and the upper end of the cylinder. The cover plate is formed with a filling opening 22 and also with an aperture 23, the former being normally closed by the core-piece, while the latter receives a lug 24 upstanding from the cylinder to hold the cover plate against any turning movement. When the removable knob 18 is locked in an operative position, the upper knob 20 bears against the cover plate to prevent the same from riding upwardly on the spindle, as would result in the aperture 23 becoming disengaged from the lug.

In the practical use of the invention, when the operative requires one or more travelers, he grasps one of the knobs of the spindle and turns the carrier disk 8 within the magazine. Attention is particularly directed to the fact that inasmuch as the opposing walls of the cylinder and the core-piece are channeled, as before mentioned, the bunches or chains of travelers are prevented from being carried by the disk toward one end of the magazine space, but instead the bunches are held by the channels and the rotation of the plate effects the agitation of the travelers, which results in the same becoming untangled. The separated travelers drop into the perforations 10 and upon a continued rotation of the disk are carried one at a

time beneath the core-piece 6 and deposited upon the inclined way 11, by which they are conducted into the shallow cup 12. The travelers so delivered may be expeditiously removed from the cup by the operative. It is to be observed that the device may be operated by turning the shaft in either direction.

When occasion demands the refilling of the magazine, the screw 19 is loosened and the knob 18 backed off, the spindle being slid vertically upwardly whereby to admit of the cover plate 21 being lifted out of engagement with the lug 24. The cover plate is then turned to bring the filling opening 22 in registry with the magazine space, and the travelers in bulk are introduced into the latter. When the knob 18 is backed off the carrier disk is released, so as to preclude the possibility of travelers being delivered in case the spindle should be accidentally turned during the filling operation. After the loading of the magazine has been completed the cover plate is restored to its normal position by reversing the above operation. The manipulation required to release the cover plate is sufficient to render the interior of the magazine comparatively inaccessible to unauthorized or playful persons, and even should the cover plate be turned to cause the filling opening to register with the magazine space, it would be almost impossible to withdraw a bunch of travelers through the former.

It is also contemplated to employ this device for holding the larger travelers which are used for heavy spinning. For this purpose a relatively thick disk 8^a is provided and is designed to be substituted for the disk 8, a washer 25 being interposed between the flange 2 and the bottom plate 3 in order to compensate for the increased thickness of the disk, as illustrated in Fig. 5. It is to be understood that a set of these interchangeable disks may be furnished with each magazine, so as to render the device susceptible of use with travelers of different sizes and thus materially increase its utility.

From the foregoing description in connection with the accompanying drawing, it will be apparent that I have provided an improved magazine traveler which is arranged to deliver the travelers one by one as needed, and thus reduces the waste to a minimum; which embodies peculiar means for coöperating with the delivering mechanism to effect the disentangling of the bunches or chains of travelers; and which is very handy and susceptible of being quickly and conveniently operated.

Among the many other advantages residing in the structure attention is called to the fact that the device requires no oiling or other attention; that it consists of comparatively few parts which are readily sep-

aratable and may be replaced by new parts if broken, at a comparatively small cost; and that it embodies to a marked degree the characteristics of simplicity, durability and efficiency and may be easily and cheaply manufactured, so as to be placed upon the market at a price not too great to prevent its general adoption.

Having thus described the invention what is claimed as new is:

1. The combination of a magazine for containing travelers in bulk, a core located within the magazine and having a channeled periphery, and means for discharging 15 the travelers from the magazine one by one.

2. The combination of a magazine having a segmental chamber for containing travelers in bulk, and means for discharging the travelers from the magazine one by one, 20 one wall of the chamber being channeled and coöperating with the discharging means to disentangle the travelers.

3. The combination of a magazine having a segmental chamber for containing travelers 25 in bulk, and means for discharging the travelers from the magazine one by one, the inner wall of the segmental chamber being channeled for engaging with the travelers, as and for the purpose specified.

30 4. The combination of a magazine for containing travelers in bulk, a core located within the magazine, and means for delivering the travelers from the magazine one by one, the opposing walls of the magazine and the 35 core being channeled and coöperating with the delivering means to disentangle the travelers.

5. The combination of a magazine having a 40 segmental chamber for containing travelers in bulk, and means for delivering the travelers from the magazine one by one, the opposing walls of the chamber being irregular and coöperating with the delivering means to disentangle the travelers.

45 6. The combination of a magazine having a segmental chamber for containing travelers in bulk, and means for delivering the travelers from the magazine one by one, the opposing walls of the chamber being correspondingly channeled, whereby the chamber is alternately relatively wide and narrow, as and for the purpose specified.

55 7. A delivering traveler magazine comprising a vertically disposed cylinder for containing travelers in bulk, a core extending radially inwardly from the side wall of the cylinder and spaced from the bottom thereof, and a carrier disk rotatable over the bottom of the cylinder and below the core to 60 deliver the travelers one by one.

8. The combination of a magazine for con-

taining travelers in bulk, a core disposed inwardly from a side wall of the magazine and arranged in spaced relation to the bottom thereof, a carrier disk rotatable over the 65 bottom of the magazine and below the core and adapted to deliver the travelers one by one, and a spindle journaled in the core for turning the disk.

9. The combination of a magazine for containing travelers in bulk, a core located within the magazine and arranged in spaced relation to the bottom thereof, the bottom of the magazine being formed below the core with an outlet, and a carrier element rotatable 75 over the bottom of the magazine and beneath the core to deliver the travelers one by one through the outlet.

10. The combination of a magazine for containing travelers in bulk, a core located 80 within the magazine, means for delivering the travelers from the magazine, a cover rotatable with respect to the magazine and formed with a filling opening normally registering with the core, and means for holding 85 the cover against any relative turning movement.

11. The combination of a magazine for containing travelers in bulk, a core located 90 within the magazine, means for delivering the travelers from the magazine, a cover rotatable with respect to the magazine and formed with a filling opening normally registering with the core, the cover being also formed with an aperture and the magazine 95 being provided with an upstanding lug adapted to enter the aperture to hold the cover against any relative turning movement.

12. The combination of a magazine for containing travelers in bulk, a core located 100 within the magazine, means for delivering the travelers from the magazine one by one, a spindle passed vertically through the magazine for operating the delivering means, a cover loosely mounted on the spindle and 105 formed with a filling opening normally registering with the core and also formed with an aperture, the magazine being provided with an upstanding lug adapted to enter the aperture to hold the cover against any relative turning movement, a knob provided at the upper end of the spindle and bearing against the cover plate to hold the same against riding upwardly out of engagement with the lug, and a second knob removably 110 mounted on the spindle below the magazine.

In testimony whereof I affix my signature in presence of two witnesses.
